UNITED STATES PATENT OFFICE.

COLVIN L. JOHNSON, OF CHICAGO, ILLINOIS.

LOCK.

1,326,270.

Specification of Letters Patent. Patented Dec. 30, 1919.

Application filed March 10, 1919. Serial No. 281,647.

To all whom it may concern:

Be it known that I, COLVIN L. JOHNSON, a citizen of the United States, and a resident of the city of Chicago, in the county of Cook and State of Illinois, have invented certain new and useful Improvements in Locks; and I do hereby declare that the following is a full, clear, and exact description of the same, reference being had to the accompanying drawings, and to the numerals of reference marked thereon, which form a part of this specification.

This invention relates to locks of the type in which a cylinder is prevented from rotating by a series of pins of different lengths until these pins have been depressed by amounts supplementary to their differences in length. The well-known Yale locks are of this type and have been used for a variety of purposes. In the present case the lock is more particularly designed for use in connection with safety devices for automobiles and in particular to locks on automobile shift levers, although not limited to such use.

25 In locks of the Yale type as heretofore constructed the parts have been made of brass or other relatively soft material so that it is easy to drill into the face of the lock escutcheon in order to cut off the pins so that 30 the rotating cylinder may be turned without a special key.

The principal object, therefore, of my invention is to provide means whereby drilling through the face of the lock may be prevented.

Other and further important objects of this invention will be apparent from the disclosures in the specification and drawings.

The invention (in a preferred form) is 40 illustrated in the drawings and hereinafter more fully described.

In the drawings:

Figure 1 is a side elevation partly in section of a change speed lever comprising a 45 Yale lock embodying my invention.

Fig. 2 is a front elevation of the escutcheon of the lock.

Fig. 3 is a section on the line 3-3 of Fig. 2.

50 Fig. 4 is a section on the line 4-4 of Fig. 3.

As shown in the drawings:

1, represents a change speed lever having a spherical part 2, about which the lever 55 turns as a pivot for the purpose of selecting

gears. Movement of the change speed lever is prevented, while the car is not in use, by means of a link 3, operating locking means not shown. The link 3, is reciprocated in a slot 14, in the change speed lever, by means 60 of a Yale lock 4. For this purpose the rotating cylinder 6, of the lock 4, is connected to the link 3, by means of a crank 5.

The lock escutcheon comprises a cylinder 6 adapted to rotate eccentrically in a cylindrical block or case 7. A series of holes are drilled in the case 7 and the cylinder 6, perpendicular to the action of rotation of the latter for the reception of pairs of pins 8 and 9. As shown, the pins 8 are of equal 65 length but the length of the pins 9 varies so that each of the pins 9, must be depressed to a different amount in order to bring the junction line between the pins 8 and 9 into register with the outer face of the cylinder 70 6 so that the latter may rotate within the case 7. The usual key hole slot 10, is provided for the insertion of a key for depressing the pins. The pins are normally pressed toward the key hole slot 10, by 75 springs 11.

It is evident that the cylinder 6 would be free to rotate in the case 7, if a hole was drilled along the line of contact of the cylinder with the case so as to cut off the pins at 80 that point. Similarly a hole drilled in the case 7, so as to cut the pins off flush with the outer surface of the cylinder 6, would have the same result. In the same way a hole drilled in the cylinder 6 so as to cut 85 the pins off flush with the inner surface of the case 7 would allow the lock to be operated.

According to the present invention however, in order to prevent the drilling of the 90 lock, hardened steel plates are arranged to cover the pins adjacent the line of contact of the cylinder and casing. This may be conveniently accomplished by providing a hardened steel cap 12 which covers the whole 95 outer surface of the lock, except that occupied by the cylinder 6. This cap 12 is preferably flanged as at 13 in order to prevent a tool being inserted between the edge of the cap and the case 7 for prying it away 100 from the lock.

In the cylinder, a hardened steel segment 15 is inserted in a lateral slot in line with the point where the pins pass from the case 7 to the cylinder. In this way, all drilling 110

of holes which would result in cutting the lock pins along the line of contact of the cylinder and case is avoided.

I am aware that various details of construction may be varied through a wide range without departing from the principles of this invention, and I therefore, do not purpose limiting the patent when granted otherwise than necessitated by the prior art.

10 I claim as my invention:

1. A lock of the type described, comprising a case, a cylinder adapted to rotate therein, a series of pairs of pins therein of uniform equal length, extending from the case into the cylinder, a hardened steel flanged cap covering the entire front of the case not occupied by the end of the cylinder and a hardened steel segment inserted laterally in 20 the cylinder in line with the points where the pins extend from the case to the cylinder, whereby cutting the pins by drilling from the front of the lock is prevented.

2. A lock escutcheon comprising a cylindrical lock casing, a hardened steel flanged cap therefor, the flange of which is arranged in an annular recess in the casing so that

its outer surface is flush with the casing, a lateral projection at the opposite end of the casing to prevent removal of the lock from the aperture in which it is located, a cylinder adapted to rotate in the casing, a series of pairs of pins extending from the case into the cylinder and a hardened steel insert in the cylinder in line with the points to where the pins extend from the casing into the cylinder.

3. A lock escutcheon comprising a cylindrical lock casing, a hardened steel flanged cap therefor, the flange of which is arranged in an annular recess in the casing so that its outer surface is flush with the casing, a cylinder adapted to rotate in the casing and a hardened steel insert in the cylinder in line with the points where the pins extend from the casing into the cylinder.

In testimony whereof I have hereunto subscribed my name in the presence of two subscribing witnesses.

COLVIN L. JOHNSON.
